ABSTRACT OF THE DISCLOSURE

A golf teeing machine in which driving of a golf ball off the tee actuates a switch to operate a motor through one cycle. A stiff cable connected to the ball tee is reciprocated by the motor. The first half of the cycle lowers the tee below the ground to a ball receiving position and the second half of the cycle raises the tee above the ground to a ball striking position.

This invention relates to an automatic golf ball teeing device, such as might be used for golf ball driving practice.

An object of the invention is to provide a golf ball teeing device embodying structural improvements which assure continuous reliability of automatic operation without frequent servicing.

Another object of the invention is to greatly reduce the number of operating parts constituting the automatic teeing device, and to simplify such parts in the interests of economical manufacture and assembly.

Another object is to provide a device of the character stated, which employs no delicate parts requiring frequent replacement or adjustment in order to keep the device in operative condition.

A further object of the invention is to provide a device of the character stated, the power requirement of which is limited to electricity alone, thereby eliminating costly installation expense and servicing problems.

A still further object is to make possible the use of low voltage electric power in the controls of the device, thereby ensuring safety of operation and conservation of the electrical elements employed in the construction thereof.

Another object of the invention is to provide an operating mechanism for an automatic ball teeing device, which will never require adjustment of any parts subsequent to assembly and installation of the device.

A further object of the invention is to provide a device of the type referred to, which cannot be disabled by adverse weather conditions, or abusive treatment.

Another object is to ensure profitable operation of the automatic ball teeing device in commercial use, and to encourage patronage by its ability to perform uninterrupted satisfactory service as expected by a patron or user.

The foregoing and other objects are attained by the means described herein and illustrated upon the accompanying drawings, in which:

FIG. 1 is a fragmentary perspective view of a ball storage and delivery magazine adapted for above-ground placement, and supporting the motor drive means of the device.

FIG. 2 is a perspective view, partly broken away, showing a ball elevator and delivery chute.

FIG. 3 is a top plan view of the driving mechanism illustrated by FIG. 1.

FIG. 4 is a cross section taken on line 4—4 of FIG. 3.

FIGS. 5 and 6 are views similar to FIG. 4, showing the drive mechanism in different stages of operation.

FIG. 7 is a vertical cross section taken through the ball chute and elevator of FIG. 2, part broken away, and showing a golf ball elevated to striking position.

2

FIG. 8 is a view similar to FIG. 7, but showing a ball in the process of being elevated to striking position.

FIG. 9 is a vertical cross section taken on line 9—9 of FIG. 7.

FIGS. 10 and 11 are fragmentary cross sections of a tee element and associated mercury switch in different positions.

FIG. 12 is a cross section taken on line 12—12 of FIG. 9.

FIG. 13 is a cross section taken on line 13—13 of FIG. 12.

FIGS. 14 and 15 are wiring diagrams showing two alternative positions of the motor-driven elevator and ball release control.

FIG. 16 is a detail view in cross section, showing the tee element of FIGS. 14 and 15 in circuit-closing position.

With reference to the accompanying drawings, FIG. 1; the numeral 20 illustrates a golf ball storage magazine 20 of considerable size, having side walls 22 uniformly spaced apart a distance slightly exceeding the diameter of a golf ball. Within the magazine a multiplicity of balls may rest vertically upon one another, for delivery from the magazine by gravity through a pipe or chute 24 fixed in the bottom wall of the magazine. The magazine preferably stands wholly above ground level in a vertical plane, with its bottom wall 26 lowermost, and perhaps sloping slightly toward chute 24 if desired. Such sloping of the bottom wall is not necessary, however.

In a preferred form of magazine 20, a ball agitator (not shown), may be incorporated therein to ensure free movement of balls into chute 24. The agitator forms no part of the present invention, and need not therefore be disclosed in detail.

As suggested by FIGS. 2 and 7, chute 24 feeds balls in succession to a receiving chute or chute extension 28 encased within a water-tight housing 30 which contains a ball release mechanism and an elevator to present balls successively into driving position above ground level. Housing 30 may be buried in the ground, with its removable cover or access plate 32 exposed at approximate ground level. The housing has a bottom wall 34, as shown.

Chute 24 may be aligned with chute 28 to feed balls thereto, and chute 28 has an open end 34 for delivery of balls in succession to a tubular elevator shaft 36 disposed vertically within housing 30. By preference, though not of necessity, the tubular elevator shaft may be square in cross section as shown, and may be stationarily mounted at one end upon the bottom wall of housing 30 by means of welds, screws, or other fasteners. At the location 34, the tubular elevator shaft is side apertured to receive balls from chute 28. The main chute 24 preferably is detachably secured to housing 30 at a flange 38, FIG. 7.

A vertically reciprocable elevator member or carriage 40 is slidable within the elevator shaft or tube 36, being upper and lower limits, FIG. 7, the shaft or tube 36 serving as a guide therefor. Carriage 40 may be elongate, and may fit slidably but non-rotatably within tube 36. Carriage 40 supports at its upper end the normally upstanding ball tee 42, to poised a ball for striking or driving by means of a golf club. Tee 42 is momentarily displaceable to an angular position when struck (FIGS. 7, 11 and 16), so as to close a switch and momentarily complete an electric circuit, as will be explained.

Carriage 40, herein disclosed as a short length of tubing by way of example, carries a fixed laterally extending stud 44 which projects through an upright elongate slot 46 in elevator tube 36. The outer end of stud 44 may carry a roller 48, to serve as a cam follower.

At a location opposite the stud 44, the carriage may be provided with one or more laterally extending studs or screws 50, which project through a second upright elongate slot 52 formed in a wall of tube 36. Studs or screws 50 support a clamp member 54 located exteriorly of tube 36, said clamp member being provided as an anchorage for one end of a flexible, but rather stiff, wire or cable 56 reciprocable within a sheath 58. A sheath anchor 60 fixes the sheath to tube 36.

From the foregoing, it will be understood that projection of wire or cable 56, in FIG. 9, will act through clamp 54 and studs 50, to lower the carriage 40 to the broken line position shown. In the lowered position of the carriage, ball tee 42 supported thereon, will assume a lowered position for receiving a ball from chute 28, FIG. 7. Upon retraction of wire or cable 56 to the full line position of FIG. 9, carriage 40 will be elevated thereby, to project the tee 42 and a ball supported thereon in position for play. Thus it will be noted that all carriage movements depend upon a simple reciprocative movement of the wire or cable 56 within sheath 58.

FIG. 1 and FIGS. 3 and 6 illustrate a simple and reliable form of means to reciprocate the wire or cable 56 for elevating and lowering the carriage 40 and its associated ball tee 42. Such means may comprise a small electric motor 60' having a drive shaft 62 rotatable at reduced speed by means of a speed reduction gear box 64 carried by the motor frame. On shaft 62 is fixed an arm or crank 66, having at its free end a roller or other abutment member 68. Intermediate the opposite ends of arm or crank 66 is a pivot 70, which provides a pivotal connection with one end of a pitman, link, or drive member 72, the opposite or free end of which as a connection 74 with wire or cable 56.

From the foregoing, it will be understood that one full rotation of drive shaft 62 will swing the arm 66 through 360 degrees, causing pitman or member 72 to execute one full advancement and one full retraction of wire or cable 56 within its sheath, to lower and then elevate carriage 40 as heretofore explained. Such movements of the cable 56 and carriage 40 will be repeated whenever motor 60 is energized according to a sequential closing and opening of the motor circuit, as will be explained.

With further reference to FIGS. 1 and 3 to 6, the numeral 76 indicates the actuating finger of a microswitch 78 or the like, of the normally closed-circuit type, whose contacts when closed supply electrical energy to motor 60. Switch 78 may be mounted upon one end of a resilient arm 80, the opposite end of which may be fixed at 82 upon a stationary bracket 84. By slightly flexing the arm 80 in one direction about anchor 82, as by means of a solenoid or electromagnet 86, the actuating finger 76 of the switch may be swung out of the path of movement of roller or abutment 68, thereby to relieve the actuating finger of pressure imposed thereon by the roller. As switch 78 is of the self-closing type, it will close the circuit of motor 60' as soon as finger 76 is relieved of the roller pressure, thereby initiating a 360 degree rotation of arm 66 on drive shaft 62.

FIG. 5 shows the switch 78 withdrawn by action of the armature of solenoid or electromagnet 86, to displace actuating finger 76 from the FIG. 4 position. Such displacement of the switch and its finger 76 permits self-closing of the switch contacts, which in turn starts motor 60 to execute a full advancement and retraction of pitman 72 and wire 56, to lower and elevate the carriage 40.

As the drive member 66 of FIG. 5 continues to rotate in the direction of the arrow, it finally reaches the FIG. 4 position at which roller 68 strikes the switch finger 76 to open the switch contacts controlling motor 60'. Motor 60' then stops, with roller 68 remaining in the FIG. 4 position to hold the switch contacts open. Any subsequent energization of solenoid or electromagnet 86 serves to withdraw switch actuator finger 76 from the pressing in-

fluence of roller 68, as in FIG. 5, to initiate a cycle of carriage movement as heretofore explained.

All of the mechanism above described may be advantageously mounted upon a side wall of magazine 20 as shown, where it is above ground and easily accessible. In practice, said mechanism may be covered by a detachable shroud or guard secured to the magazine wall. The bracket 88 may carry a simple transformer 90 supplying a safe low-voltage electric current for operating the solenoid or electromagnet 86 to be energized through a switch or contactor 92 which closes a circuit through the solenoid or electromagnet whenever ball tee 42 is momentarily tilted incident to driving a ball from the tee.

Ball tee 42 may be constructed of supple molded rubber or the like, to provide an upstanding hollow shank 93, and a base 94 having an annular depending flange 96. The flange fits snugly into the open upper end of carriage member 40, while the base closes said upper end making a water-tight joint. Upon the lower face 98 of the flexible base may be mounted the electrical contactor 92, preferably in the form of a tiltable mercury switch, which upon tilting in one direction closes an electric gap between the internal ends of conductors 102 and 104 embedded in an end of the capsule which forms the body of switch 92. A ball 106 of mercury within the capsule will shift to close the gap between the inner ends of conductors 102 and 104 whenever the base 94 is flexed incident to tilting of shank 93 as the shank or a ball superposed thereon is struck by a golf club. In the normal vertical position of the tee, the switch 92 is open-circuited.

In the wiring diagrams, FIGS. 14 and 15, switch 92 is shown in the normal open-circuited condition. Electric current from line wires 106 and 108 may energize motor 60, provided that switch 76 is closed by relief of pressure imposed thereon by roller 68. The secondary winding of transformer 90 is connected in series with switch 92, and with the coil of solenoid or electromagnet 86. Therefore, when the tee 42 is tilted as the result of driving a ball therefrom, switch 92 will momentarily close the circuit of solenoid or electromagnet 86, to remove the actuator 76 of switch 78 from the depressing action of roller 68. Relieved of pressure, actuator 76 will spring up to close the contacts of switch 78 (FIG. 15), for completing the circuit of motor 60'. Motor 60' accordingly will operate to drive the carriage by means of wire or cable 56, until roller 68 arrives at the FIG. 14 position to open the contacts of switch 76.

With reference to FIG. 15, switch 78 is shown withdrawn from the influence of roller 68. It must be understood that such withdrawal is momentary only, due to the brief energization of solenoid or electromagnet 86 by the momentary closing of tee switch 92. Accordingly, the switch 78, being biased yielding away from the armature of the solenoid or electromagnet 86, will return to the FIG. 14 position. By this time, however, roller 68 will have been advanced by rotation of drive shaft 62, substantially as depicted by FIG. 5, so as to have no physical contact with the actuator 76 of switch 78. Once the roller 68 has moved from the vicinity of switch actuator 76, as in FIG. 5, the spring biased switch 78 may return to the FIG. 4 position at which roller 68 will be effective to actuate it only when said roller completes its cycle of movement about shaft 62, as shown by broken lines in FIG. 6.

A simple mechanical means is provided for replacing a ball driven from the tee. Replacement balls are supplied through the inclined chutes 24 and 28, from magazine 20. The feeding of balls is controlled by the vertical movements of carriage 40 resulting from the cyclic energization of motor 60'. As previously mentioned, carriage 40 carries a roller or cam follower 48 which moves therewith as the carriage travels between its upper and lower limits.

The numeral 110 (FIG. 7) indicates a first control arm mounted at one end upon a fixed pivot 112 carried by chute 28. The free end portion 114 of said arm rests normally upon roller 48. A second control arm 116 likewise

may be pivoted at 118 upon chute 28, and has a free end portion 120 in the path of movement of roller 48. Intermediate their ends, the arms 110 and 116 may be yieldingly urged toward one another by a connecting tension spring 122.

Arm 116 carries a ball release pin or plunger member 124, which by the action of spring 122 projects normally through an opening 126 in the bottom of chute 28. Member 124 accordingly will normally preclude gravitational movement of the leading ball toward elevator tube 36.

The arm 110 carries a ball release pin or plunger member 128, which upon descent of said arm 110 about pivot 112, may enter an opening 130 in the top wall of chute 28 to intercept a ball following the leading ball. Release pin or member 128 is normally withdrawn from chute opening 130, by reason of roller 48 supporting arm 110 in an elevated position, FIG. 7. Spring 123 however, biases arm 110 against the roller 48, so that upon descent of carriage 40 and roller 48, arm 110 will follow until pin 128 fully enters the opening 130 to intercept the second ball in chute 28. Further descent of the carriage causes roller 48 to strike and depress the second arm 116 to the broken line position of FIG. 7, thereby to withdraw pin 124 and release the first ball for entry into elevator tube 36, whereby this time the tee 42 has been lowered to accept the released ball according to FIG. 7.

After a ball has been released onto tee 42, carriage 40 rises to its upper limit and presents the ball for striking. During the upward motion of the carriage, spring 122 acts to elevate the arm 116 and its pin 124, for holding the next ball in position for subsequent release. It will be noted that the arrangement of pins 128 and 124 ensures the release of but one ball at a time, during each lowering and elevating cycle of carriage 40. As was previously explained, a cycle of carriage movement is initiated by a momentary closing of the contacts of tee switch 92, incident to tilting of the tee when either the tee or the ball thereon is struck by a golf club.

Whereas two springs 122 and 123 are shown anchored at 125 upon chute 28, a preferred arrangement is to omit the anchorage at 125 and employ a single tension spring spanning the arms 110 and 116 for yieldingly urging the arms toward one another. In either case, arm 110 normally is yieldingly held against roller 48, and arm 116 is stopped against chute 28 at the base of pin 124 until roller 48 descends to lower the arms to the broken line position, FIGS. 7 and 12.

Arms 110 and 116 move in a common vertical plane alongside the elevator tube 36. It may be noted also that the conductors 102 and 104 for tee switch 92, are flexible so as to coil near the bottom of elevator tube 36 whenever the carriage 40 is lowered. Conductors 102 and 104 may emerge from housing 30 through a rubber ferrule 132, for connection with the coil of electromagnet or solenoid 86 and the secondary winding of transformer 90, in accordance with the wiring diagrams of FIGS. 14 and 15. Tee switch 92 is preferably though not necessarily a mercury switch.

The apparatus of the invention utilizes no power other than electric current, and employs no delicate or complex electrical components requiring frequent adjustments or replacements. Moreover, all working parts which may require attention are readily accessible, and protected from adverse weather conditions or abuse. The device employs a minimum number of working parts, which are of simple and durable construction, thereby avoiding any need for frequent servicing, adjustments, or replacements. The resultant reliability of operation is of primary importance in commercial installations.

It is to be understood that various modifications and changes may be made in the structural details of the device, within the scope of the appended claims, without departing from the spirit of the invention.

What is claimed is:

1. An automatic golf ball teeing device, which comprises in combination: a chute for delivering balls from a magazine; a ball elevator disposable below ground level, including a carriage reciprocable between upper and lower limits, and means for guiding the carriage in said movements; a displaceable ball tee movable with the carriage, for disposition to locations above and below ground level; operating means including an electric motor connected in an electric circuit, for moving the carriage through a cycle of downward and upward movement between the limits aforesaid, upon closing of the motor circuit; electric means including a normally open-circuited contactor closable momentarily upon each displacement of the ball tee, to momentarily close the motor circuit for actuating the operating means aforesaid; means associated with said operating means, for maintaining the closed-circuit condition of the motor circuit until the carriage moves downwardly then upwardly to the upper limit of travel, and to then open the motor circuit; and means operative during the cyclic movement of the carriage between its upper and lower limits, to release a ball from the chute onto the tee, for presenting the released ball for striking above ground level when the carriage reaches the upper limit of carriage travel.

2. The device as specified by claim 1, wherein the operating means for the carriage includes a member reciprocable by the motor; a flexible cable having one end fixed to said member for longitudinal reciprocation thereby; and means fixing the opposite end of the cable to the carriage, with said opposite end movable in the direction of carriage reciprocation.

3. The device as specified by claim 2, wherein the motor, the reciprocable member, and that end of the flexible cable which is fixed to said member, are located remotely from the ball elevator and above ground level.

4. The device as specified by claim 3, wherein the combination includes a ball magazine located above ground level for feeding balls to the chute; and means for supporting upon the magazine the motor, the reciprocable member, and a portion of the length of the flexible cable driven by said reciprocable member.

5. The device as specified by claim 1, wherein the operating means for the carriage includes a member reciprocable by the motor; a flexible cable having one end fixed to said member for longitudinal reciprocation thereby; and means fixing the opposite end of the cable to the carriage, with said opposite end movable in the direction of carriage reciprocation; said motor, said reciprocable member, and that end of the flexible cable which is fixed to said member, being located above ground level.

6. The device as specified by claim 5, wherein is included a ball magazine located above ground level for feeding balls to the chute; and means for supporting upon the magazine the motor, the reciprocable member, and a portion of the flexible cable.

7. The device as specified by claim 1, wherein the operating means for moving the carriage includes a flexible cable longitudinally reciprocable by the motor aforesaid, said cable having an end secured to the carriage for reciprocation longitudinally of the path of carriage movement.

8. An automatic golf ball teeing device, which comprises in combination: a chute for delivering balls from a magazine; a ball elevator disposable below ground level, including a carriage reciprocable between upper and lower limits, and means for guiding the carriage in said movements; a displaceable ball tee mounted upon the carriage for movement to locations above and below ground level; operating means including an electric motor connectable in an electric circuit, for moving the carriage through a cycle of downward then upward movement between the limits aforesaid, upon closing of the

motor circuit; means operative incident to displacement of the ball tee, for closing the motor circuit and thereby energizing the motor to effect a single cycling of the carriage first downwardly then upwardly; and means operative during the cyclic movement of the carriage between its upper and lower limits, to release a ball from the chute onto the tee, for presenting the released ball for striking above ground level when the carriage reaches the upper limit of carriage travel at the end of a cycle; abutment means carried by the carriage; a said ball release means comprising a pair of plungers projectable through openings in the delivery chute spaced apart lengthwise of the chute a distance approximating the diametral dimension of a ball, a pair of elongate arms each carrying a plunger, said arms each having an end rockable upon a stationary pivot, and each having an opposite free end disposed alongside the carriage guiding means in close proximity thereto, said free ends being movable in the path of travel of the abutment means on the carriage, one above and one beneath said abutment means for concurrently projecting one plunger from the chute during descent of the carriage to its lower limit of travel, thereby to release a leading ball from the chute onto the tee while obstructing travel of a ball following the leading ball; and means constantly yieldingly urging the free ends of said arms toward said abutment means on the carriage.

9. The device as specified by claim 8, wherein the abutment means on the carriage comprises a freely rotatable roller mounted upon a stud extended laterally from the carriage.

10. An automatic golf ball teeing device, which comprises in combination: a magazine for golf balls, and a chute for delivering balls from the magazine; a ball elevator disposable below ground level, including a carriage reciprocable between upper and lower limits, and means for guiding the carriage in said movements; a laterally displaceable ball tee mounted upon the carriage for movement to locations above and below ground level; a normally open-circuited electrical contactor associated with the tee, to be closed-circuited momentarily upon momentary lateral displacement of the tee; a first electric circuit including a driving motor and a self-closing switch in series connection, said switch including an actuator to be depressed for opening the contacts of said switch; a shaft rotatable by said motor, and an arm rotatable with said shaft through 360 degrees of movement; means shiftably supporting the self-closing switch actuator for movement from a normal position within the path of movement of the motor-driven arm, to a displaced position out of said path of movement; a second electric circuit including an electromagnetic means in series connection with the electrical contactor of the tee, said electromagnetic means including an armature energizable through said electrical contactor upon momentary lateral displacement of the tee, for momentarily displacing the actuator of the self-closing switch from the path of movement of the arm, causing said self-closing switch to close the motor circuit throughout the 360 degree movement of the arm driven

by the motor shaft, until said arm subsequently depresses the switch actuator to open the contacts thereof and de-energize the motor, and a flexible cable having an end secured to the carriage and reciprocable longitudinally therewith, said cable having an opposite end driven in correspondency with movements of said arm to impart reciprocative movements to said carriage between the upper and lower limits aforesaid.

11. The device as specified by claim 10, wherein the combination includes release means for relasing a ball onto the tee from said delivery chute, upon disposition of the carriage to approximately the lower limit of carriage travel.

12. The device as specified by claim 10, wherein the combination includes release means for releasing a ball onto the tee from said delivery chute; and means including a member carried by the carriage, for actuating the ball release means to release a ball upon disposition of the carriage to approximately its lower limit of travel.

13. The device as specified by claim 10, wherein the ball release means includes: a pair of plungers projectable through openings in the delivery chute spaced apart lengthwise of the chute a distance approximating the diametral dimension of a ball, movable means supporting said plungers, and abutment means carried by the carriage for actuating said movable means to project one plunger into the chute, and to withdraw the other plunger from the chute during descent of the carriage, thereby to release a leading ball from the chute onto the tee while obstructing travel of a ball following the leading ball.

14. The device as specified by claim 13, wherein the movable means supporting the plungers comprises a pair of elongate arms each carrying one of the plungers, said arms each having an end rockable upon a stationary pivot, and each having an opposite free end disposed alongside the carriage guiding means in close proximity thereto, said free ends being movable in the path of travel of the abutment means on the carriage, one above and one beneath said abutment means; and means constantly yieldingly urging the free ends of the arms toward said abutment means on the carriage.

15. The device as specified by claim 14, wherein said abutment means comprises a roller mounted upon a stud extended laterally from the carriage, the stud being fixed upon the carriage for bodily movement therewith.

16. The device as specified by claim 10, wherein the end of the flexible cable secured to the carriage is disposed below ground level, and the opposite driven end of said cable is disposed above ground level.
